UNITED STATES PATENT OFFICE.

LEO STEIN, OF ROCHESTER, NEW YORK.

DESIGN FOR A COFFIN.

SPECIFICATION forming part of Design No. 19,309, dated September 10, 1889.

Application filed August 3, 1889. Serial No. 319,687. Term of patent 14 years.

To all whom it may concern:

Be it known that I, LEO STEIN, a citizen of the United States, residing at Rochester, in the county of Monroe and State of New York, 5 have invented and produced a new and original Design for Burial-Casket Lids, of which the following is a specification, reference being had to the accompanying drawings, forming part thereof.

10 Figure 1 is a plan view of a burial-casket lid, showing my design; and Fig. 2 is a sectional view taken on line xx , Fig. 1, illustrating the contour of the parts thereof, these two views being deemed necessary to fully illustrate my design.

15 The leading feature of my design consists in a curved or rounded lid having its outer portion of its central surface or panel depressed below the plane of a bordering edge 20 or molding and a cross-bar arranged in the central part of the bordered surface of the lid and raised above the plane of the head and foot sections of the lid on either side of the cross-bar.

25 a is the central surface or panel of the lid, of rounding or curved contour, and having its outer portion depressed below the plane of a bordering edge or molding b . This depressing of the central portion of the lid below a

raised edge presents a pleasing and novel effect, which is further increased by forming the central portion of rounding contour. The cross-bar c is arranged between the two extremities of the lid and is raised above the plane of the rounding central panel of the 35 lid, dividing the same into a head-section d and foot-section d' and greatly adding to the appearance thereof by the effect occasioned by depressing said head and foot sections below the plane of a surrounding raised surface 40 formed by the raised edge b and the cross-bar c .

What I claim is—

The design for a burial-casket lid herein shown and described, the same comprising 45 the central surface or panel rounding or curving toward the edge of the lid, and a bordering edge or molding raised above the plane of said central surface or panel, as set forth.

In testimony whereof I have hereunto signed 50 my name, in the presence of two attesting witnesses, at Rochester, in the county of Monroe, in the State of New York, this 27th day of July, 1889.

LEO STEIN.
